UNITED STATES PATENT OFFICE.

ALLEN N. SPOONER, OF NEW YORK, N. Y.

HYDRAULIC BORING AND WELL-DRIVING APPARATUS.

1,036,364.

Specification of Letters Patent. Patented Aug. 20, 1912.

Application filed May 28, 1912. Serial No. 700,147.

To all whom it may concern:

Be it known that I, ALLEN N. SPOONER, a citizen of the United States, residing at New York city, in the borough of Manhattan and State of New York, have invented certain new and useful Improvements in Hydraulic Boring and Well-Driving Apparatus, of which the following is a full, clear, and exact description.

10 This invention relates to apparatus for boring earth strata hydraulically and for driving well tubes and like operations.

Heretofore it has been common in sinking wells to use two different sized pipes in such operations, one disposed within the other, preferably concentrically, the outer of said pipes constituting in effect a casing or caisson and the inner of these pipes being of materially less diameter and conveying water or the like under pressure to a point adjacent the lower extremity of the outer pipe or casing, the jet of water emerging from the interior pipe forming a cavity in the sand, gravel or other material through which the pipes are being driven, immediately below and in fact more or less around the lower extremity of the outer pipe or casing so that the latter may thereafter be driven forcibly downwardly until 20 the end thereof touches the bottom or is driven slightly into the bottom of this cavity. When the strata through which the well or the like is being driven is sand or other not too solidly formed or united material, there is a tendency, as soon as the water supply is cut off, for the walls of the hydraulically formed cavity to collapse. In fact most wet sands will act in this fashion; behaving more or less like quicksand. 25 As a result of this action the downward advance of the outer pipe at each step is quite often very limited amounting in some cases to only a very few inches or even less. Furthermore this operation, as usually conducted in practice, necessitates the complete removal of the interior or water supplying pipe before the outer pipe is struck by the driving weight or plunger. This operation consumes considerable time and involves 30 what I have found to be a needless expenditure of labor; since both the inner and outer pipes, when the boring is to be of considerable depth, are necessarily made up of relatively short lengths or sections; these 35 pipe sections usually being about five feet in length and the withdrawal of the inter-

rior pipe preparatory to each driving operation necessitating the uncoupling of the inner pipe sections which thereafter must be again coupled up after the outer pipe has 40 been driven downwardly as far as it can be, preparatory to the reapplication of the water jet.

One of the principal objects of my invention is to overcome this difficulty and to 45 so construct the apparatus that the outer pipe or casing may be forcibly driven down by the impact of a weight or hammer upon the upper extremity thereof while simultaneously water under pressure is delivered 50 through the interior pipe.

I have further aimed to adapt the novel apparatus in question for use with pile driving appliances as at present constructed.

The preferred form of the device is furthermore of extreme simplicity and is both durable and inexpensive to manufacture.

These and other objects of my invention will be hereinafter referred to and the novel elements and combination of elements whereby they may be attained will be more particularly set forth in the claims appended hereto.

In the accompanying drawing which forms a part hereof and in which like reference characters designate like parts throughout the several views, I have exemplified a preferred construction; but I am aware that various changes and modifications may be made herein within the purview of my invention and hence desire to be limited only by the scope of the said claims.

Referring to the drawings: Figure 1 is an elevation of the said apparatus showing sections of the pipe in position in the earth. 95 Fig. 2 is an enlarged detail section of the driving head and of the pipe sections adjacent thereto. Fig. 3 is a detail of the said driving head viewed in elevation at right angles to the view of the same shown in 100 Fig. 2. Fig. 4 is a top view of the said driving head. Fig. 5 shows a modified construction of the drive head and spout.

In operations of this character the material to be bored commonly occurs in strata 105 so that for example, as shown in Fig. 1, an upper layer 1 may be earth; a second layer 2, sand, gravel, or the like, etc. A suitable frame or housing 3 is erected or disposed preferably immediately above the point 110 where the bore is to be made. The frame shown in Fig. 1 is of a well-known construc-

tion commonly employed in well driving. It provides guide-ways for a weight or plunger, the upper extremity of which is supplied with a trip clutch 5; a cable, rope, or the like, 6, extending upwardly from this clutch around a pulley 7 and downwardly therefrom to a drum 8. When the weight is drawn upwardly to substantially the top of the frame 3 the clutch 5 engages the trip 10 crown 9 in a well-known manner which effects the release of the weight allowing the latter to descend under the influence of gravity and to violently impact upon the drive cap or striking block 10. This cap is 15 secured upon the upper extremity of a pipe section 11, which is the uppermost of a series of similar sections joined together by the couplings 12 and constituting the casing or outer pipe which as a whole has been 20 broadly designated 13. Within the casing 13 is the water supply pipe 14, the sections of which are preferably of substantially the same length as the sections of the outer pipe or casing; being joined together by couplings 15 in a well-known manner. In practice the inner pipe may be for example, $\frac{3}{4}$ " iron pipe and the outer pipe sections may be of 2" pipe.

I have shown at 16 a source of water, for 30 example, which is to be delivered under pressure through the pipe 14, a pump 17 being provided for this purpose. The latter is connected to a cross pipe 18 secured to the upper extremity of the pipe 14, in 35 any suitable fashion; as by means of a section of flexible hose 19, or the like. The cross pipe 18 is connected to the upper section of the inner pipe preferably by means of a T 20; since thereby an additional section of pipe 18' may be aligned with the cross pipe 18 so as to provide a handle whereby the inner pipe may readily be elevated when desired. The pipe sections 18, 18' and the T 20 are received into a slot 21 in the head 40 10, said slot preferably extending downwardly from the upper surface of this element a sufficient distance to insure against inadvertent striking of the weight 4 thereagainst. When the inner pipe and its head 45 formed by these sections 18, 18' is disposed with respect to the driving head 10 in the manner shown in Figs. 1, 2 and 3, the driving head may be forcibly struck by the weight 4 whereby to cause the casing 13 to be driven 50 down into the soil, without liability of injury to the water supply pipe or its connections; and it should further be observed that this construction permits of the weight 4 being of the type now commonly in use; no 55 special apparatus other than the drive head and cross pipe being necessitated. As a result of this construction also, it is possible to continuously supply water through the inner pipe while the casing is being thus driven down by successive impacts upon the

upper extremity thereof. A further advantage of this construction resides in the fact that since the inner pipe virtually depends from the striking block, its weight advantageously co-acts with the weight of the casing to force the latter into the earth. As the inner pipe is lengthened this auxiliary weight becomes very considerable and the progress of the casing through the soil or sand under the jarring action of the driving weight or plunger is materially expedited.

The operation of the device is as follows: Assuming that the two sections shown in Fig. 1 have entered the strata to be penetrated and that water is being continuously supplied from the pump 17, the jet of water emerging from the inner pipe forms the cavity 22 by loosening the soil or sand in the usual manner and conveying the thus loosened material up through the space between the inner and outer pipes from whence it emerges through the spout 23.

It will be understood, of course, that I do not desire to be limited to the particular disposition of the spout 23 which has been shown in the drawings since said spout may either be directly connected to the drive head, as shown in Fig. 1, or may be connected to a T, for example, therebelow, as shown in Fig. 5.

The lower extremity of the casing will be driven downwardly into the cavity 22 simultaneously with the issuance of jet of water into said cavity so that by practically no 100 possibility can its progress be checked by reason of the influx of loose soil or sand into the path thereof, in the manner previously described.

When boring through sand it may be 105 noted that it is desirable to maintain the lower extremity of the inner pipe a short distance within the end of the lower section of the casing, to avoid excessive displacement of the sand laterally disposed with 110 respect to the casing. After the casing has been driven down substantially the length of a section thereof, it obviously then becomes necessary to disconnect the water pipe from its source of supply and to insert thereinto 115 an additional section of pipe, the same operation being performed upon the casing. To do this, however, it is merely necessary to raise the water pipe by means of the handle-like portions of the same which project laterally through the slot upon either side of the driving head and to then unscrew the T 20 from said pipe, coupling in the additional water pipe section in the usual manner after the additional casing section has been installed. To effect this operation the weight 4 is elevated a sufficient distance to permit of the insertion of additional pipe sections and it is to be particularly observed 120 that it is practically never necessary to dis- 125 130

connect the several sections of the interior pipe which have already been inserted into the casing.

Having thus described my invention, what I claim is:

- 5 1. In hydraulic boring and well-tube driving apparatus, the combination of an outer casing, a water supply pipe adapted for insertion into said casing and a drive head 10 for said casing, said pipe having a lateral extension at its upper extremity through which water may be delivered into said pipe, said drive-head being recessed for the reception of said lateral extension.
- 15 2. In hydraulic boring and well-tube driving apparatus, the combination of an outer casing, a water supply pipe adapted for insertion into said casing and a drive-head for said casing, said pipe having a 20 lateral extension at its upper extremity through which water may be delivered into said pipe, said drive-head being slotted for the reception of said lateral extension, the slot therein extending downwardly from the 25 upper surface of said drive-head.
- 30 3. In hydraulic boring and well-tube driving apparatus, the combination of a casing with means for driving said casing into an earth strata, said means comprising a water pipe of smaller diameter than said casing disposed within the latter, a driving weight, and means for supporting said water pipe from said casing whereby the weight of said pipe may supplement the

weight of the casing during the driving 35 operation.

4. In hydraulic boring and well-tube driving apparatus, the combination of a casing with means for driving said casing into an earth strata, said means comprising 40 a water pipe of smaller diameter than said casing disposed within the latter, a driving weight, and means for supporting said water pipe from said casing whereby the weight of said pipe may supplement the 45 weight of the casing during the driving operation, said supporting means including a cross-pipe, the interior of which is in communication with said water pipe.

5. In hydraulic boring and well-tube 50 driving apparatus, the combination of an outer casing, a water-supply pipe adapted for insertion into said casing, said pipe having a lateral extension at its upper extremity through which water may be delivered into said pipe, a driving weight 55 normally above said extension, and means whereby said lateral extension may be operatively disposed below said weight for supplying water substantially continuously to 60 said pipe while said driving weight is in operation.

In witness whereof I subscribe my signature, in the presence of two witnesses.

ALLEN N. SPOONER.
